H. E. KINCHELOE.
CHAIR DESK.
APPLICATION FILED MAR. 5, 1921.

1,426,297.

Patented Aug. 15, 1922.

INVENTOR HERBERT E. KINCHELOE,
by R. George Onig Attorney.

UNITED STATES PATENT OFFICE.

HERBERT E. KINCHELOE, OF MAPLEWOOD, MISSOURI.

CHAIR DESK.

1,426,297.

Specification of Letters Patent. Patented Aug. 15, 1922.

Application filed March 5, 1921. Serial No. 449,860.

To all whom it may concern:

Be it known that I, HERBERT E. KINCHELOE, a citizen of the United States, residing at the city of Maplewood, in the county of 5 St. Louis and State of Missouri, have invented a new and useful Chair Desk, of which the following is a specification.

My invention relates to improvements in chair desks, and more particularly to a chair 10 leg and a desk attachment, having a support over the leg, capable of a wide range of adjustments relative to the chair seat for adaptation to many individual requirements and also capable of folding over the leg to 15 occupy a minimum of space when not in use.

My object is to provide a chair desk, of simple, durable and inexpensive construction, 20 whose top may be raised or lowered, its "writing" angle selectively varied, its position shifted in selective positions laterally with respect to the seat and which may be bodily folded to occupy a substantially vertical position to one side of the chair leg in front of 25 the seat, whereby the desk may be readily adapted to the user's individual requirements, shifted to clear the space in front of the chair and folded to permit the bringing together of a plurality of similarly 30 constructed chair desks.

My improvements consists in the novel construction, arrangement and combination of parts as hereinafter fully, clearly and concisely set forth, definitely pointed out in 35 my claims and illustrated by the accompanying drawing, in which—

Fig. 1 is an elevation of a chair desk embodying my improvements, with the top in writing position.

Fig. 2 is a front view of the chair desk 40 with the top folded to non-using position.

Fig. 3 is a perspective view of the chair leg which constitutes a support for the desk.

Fig. 4 is a perspective view of a fixture 45 which is secured to the leg in a manner to be adjusted vertically, horizontally and angularly relative to the leg.

Fig. 5 is a perspective view of one of a pair of standards over which the desk is 50 mounted.

Fig. 6 is a perspective view of the slotted mounting for the desk, and

Fig. 7 is a plan view of the parts assembled, showing by dotted lines the chair and 55 desk top.

Referring by numerals to the drawings, 10 designates the chair, whose seat 11 is provided adjacent its front, right hand corner with a forwardly projecting extension 12 and whose round, or equivalent, 13 carries 60 a tenon 14.

The numeral 15 designates a special chair leg of oblong section, having a height greater than the chair seat, and arranged for connection with the chair proper by means of the 65 recited extension 12 and tenon 14, as best shown in Figs. 1 and 2.

In its forward and rearward margins interjacent the plane of the chair seat 11 and the upper margin the chair leg 15 is provided with bolt openings 16 having vertical trends and for a reason hereinafter made clear the forward margin, as at 17, is inclined upwardly and rearwardly from the forward bolt opening 16. 70

By preference the bolt openings 16 are formed as simple notches in the chair leg and in order to retain bolts therein I provide keepers 18 in the form of simple metallic straps, secured by screws over the notches. 80

The numeral 19 designates a sleeve of rectangular, oblong section, whose minor dimension is comparable with the thickness of the leg 15 and whose major dimension is greater than the spacing of the bolt openings 85 16, whereby the sleeve, when fitted over the leg, will be capable of movements vertically, forwardly and rearwardly and angularly relative to the leg, but, be held against lateral canting thereover. 90

In each side of the sleeve there is formed a pair of slots 20 for the reception of the bolts 21 which extend through the openings 16 in the leg and which are provided with hand wheels 22 whereby the sleeve may be readily 95 selectively positioned relative to the leg.

At each of its ends, that is, forward and rearward faces, the sleeve 19 carries a standard 23 which rise to heights above the chair leg 15 and which are perforated, to provide 100 bearings 24, adjacent their upper ends. Extended through the standards and supported by the bearings 24 is a bolt 25 having a hand wheel 26 which constitutes a support for the desk top. 105

The top is preferably constructed of wood and equipped with the ordinary appurtenances, such as the pencil groove 27, (shown only by dotted lines) guard rails such as 28, ink-well 29, (shown only by dotted lines) and 110

with warp rails and the like, as are common, which were not deemed necessary to illustrate.

Fixed to the underneath face of the top 5 is a pair of parallel sills 30 arranged for fitment between the standards 23 and which bear the slots 31 to receive the bolts 25.

By preference the two sills are constructed as a unit, and of sheet metal, whereby they 10 may be made of relatively light material, be relatively trussed and serve as warp preventing means for the wooden desk top.

By referring to Fig. 1 it will be obvious that by reason of the clamp bolts 21, the 15 bolt openings 16, in the chair leg and the slots 20, in the sleeve 19, that the height of the desk may be varied; that the desk top may be positioned and held in a horizontal position or at selective angles relative to the 20 horizontal, and that the desk top may be moved and held in selective positions forwardly and rearwardly with respect to the chair seat. The recited margin 17 of the chair leg allows a maximum rearward swing 25 of the forward standard 23.

By referring to Fig. 2 it will be obvious that by reason of the standards 23, clamp bolt 25 and slotted sills 30 that the desk top, may be swung bodily from writing position, 30 as in Fig. 1 to a position along the side of the chair in front of the seat, leaving the space, in front of the seat, clear and permitting close grouping of a number of similarly constructed chairs.

35 At the top of the sleeve 19 there are the laterally extending flanges 32 and 33, the former coacting with the sills 30 to prevent the sills from coming in contact with the leg 15 when the top is folded over the leg to 40 non-using position, as best shown in Fig. 2.

The flange 33 coacts with shoulders 34 on the sills 30 to prevent lateral displacement of the desk top when the same is in writing position (as shown by broken lines in Fig. 2) and it is to be observed that the sills are 45 both supported over the top of the sleeve 19 and held against rocking thereover downwardly and to the left hand side of the chair leg, but, are free to be lifted and turned on the bolt 25 to their folded position vertically 50 along the side of the chair leg.

Having thus described my invention, what I claim as new therein and desire to secure by Letters Patent of the United States, therefor, is—

1. In a device of the class described, a leg having a bolt opening therein, a fitting having a bolt opening therein disposed at an angle relative to the bolt opening in the leg, means extended through said openings for 60 clamping the fitting to the leg, a bearing carried by the fitting, a slotted sill and means for pivotally securing the sill to said bearing.

2. In a device of the class described, a leg of oblong section, a sleeve for fitment thereover, there being openings having relatively angular trends in said leg and sleeve, a clamp comprising an element for extension through said openings, standards, having 70 bearings, rising from said sleeve, a sill, and means for pivotally securing the sill and standards relatively.

3. A desk attachment for chairs, comprising a fitting, means for adjustably securing the fitting to the chair, a sill for supporting the desk top, means, comprising a clamp, for pivotally securing the sill upon said fitting, and means for locking the sill against lateral movement over said fitting.

HERBERT E. KINCHELOE.
